UNITED STATES PATENT OFFICE.

GRANVILLE F. GREENING, OF NEW YORK, N. Y., ASSIGNOR TO WILLIAM S. SEMPLE, OF MAHWAH, NEW JERSEY.

TABLET-HOLDER, &c.

1,160,161.

Specification of Letters Patent.

Patented Nov. 16, 1915.

Application filed August 21, 1914. Serial No. 857,965.

To all whom it may concern:

Be it known that I, GRANVILLE F. GREENING, a subject of the Kingdom of Great Britain, residing at the borough of Brooklyn, in the county of Kings, city and State of New York, have invented certain new and useful Improvements in Tablet-Holders, &c., of which the following is a specification.

10 The object of my invention is to provide a tablet-holder for use by stenographers, etc., for holding loose-leaves, stenographers' note-books, tablets, etc., of a simple and cheap form of construction; easily 15 actuated for the removal of used leaves, books or tablets, and of such form as to be easily and instantly adapted for use in the taking of stenographers' notes, as for use as a stand in the transcription 20 thereof upon the typewriter, etc.

To such ends my invention consists in substance of a board, plate, etc., of any suitable material, usually wood, a securing device on one face of the plate for removably 25 securing thereon the loose-leaves, book or tablet; and a supporting footpiece pivoted to the edges of the board, etc., on the opposite side, for supporting the board in an inclined position for purposes of transcription.

Said invention is fully shown in the following specification, of which the accompanying drawing forms a part, wherein similar letters of reference designate like or 35 equivalent parts, wherever found throughout the several views; and in which:—

Figure 1, is a side view, in perspective of my improved form of tablet-holder, in the transcribing position; the note-taking position being shown in the dotted lines; and Fig. 2, is a front face view of the upper portion of the plate or board showing the securing device, or spring ring-clip, in the open and releasing position, ready for the 45 insertion of a new body of loose-leaves, note-book or writing-tablet.

Referring to the drawings:—the reference letter A designates the back-board or plate, usually of light wood, provided on 50 the rear surface adjacent to the lower end with the transverse slot B, adapted to receive the straight bottom-bar C, of the supporting foot-piece D, usually of brass, or other suitable metal bent into the angular 55 U form clearly shown by Fig. 1, the side-

pieces E, being pivotally secured to the edges of the plate or board A, by pivot-bolts or screws F, and being provided with the slot G, co-acting with the stop-studs screws or bolts H, secured in the edges of the board or plate, to lock such foot-piece in the transcribing supporting position shown in Fig. 1, in full lines; (the position of the foot-piece in the note-taking position being shown therein in dotted lines;) 60 in which position it will be seen that the bottom bar C of the foot-piece lying in the slot B, the board or plate can be placed flat upon a table or other surface.

At the upper end of the board or plate 70 A, and on the surface opposite to the slot B, is a lock-plate I, usually of sheet brass, etc., preferably of the form shown in Fig. 2, having the upper side-wings L, and in the narrower rear portion M being provided 75 with the hinge-coil or bead N to receive the central hinge bar O, of the securing ring-clip P, formed of resilient spring wire, and bent up at the ends into the securing rings or coils Q, provided at the ends with outwardly facing square shouldered securing slots R, adapted to spring back under the outer sides of the lock-slots S, as shown at F, of Fig. 2, so as to lock such ring-clips 80 against accidental displacement, when in 85 the tablet or leaf securing position shown in Fig. 1; the release and reinsertion of such securing arches in the lock-slots, being brought about by springing them inward toward one another.

In order to give a firm stand to the device when in the transcribing position as shown in Fig. 1, the lower end of the board or plate is beveled from front to rear, as shown at T of Fig. 1.

I claim:

1. In a device of the class described, a board, a supporting foot-piece pivoted to the board, having a bottom-bar adapted to lie in a transverse slot in the board when folded down thereon; a stop-stud limiting the movement of the foot-piece when thrown into the open and board supporting position; and a securing-clip secured upon the board on the side opposite to the slot for 100 removably securing a body of leaves, etc.

2. In a device of the class described, a board, a supporting foot-piece having a straight bottom-bar with side-pieces extending therefrom at a right angle; pivot studs 110

securing the side-pieces of the foot-piece to the board; a stop limiting the pivotal movement of the foot-piece in one direction; a transverse slot in the board to receive the bottom bar of the foot piece when swung to the limit in the other direction; and a clip for removably securing a body of leaves, etc., to the board.

Signed at the borough of Manhattan, city, county and State of New York, this 17th day of August, 1914.

GRANVILLE F. GREENING.
